UNITED STATES PATENT OFFICE.

JOHN T. HOWIESON, OF NEW YORK, N. Y., ASSIGNOR, BY MESNE ASSIGNMENTS, OF ONE-HALF TO BURROUGHS ADDING MACHINE COMPANY, OF DETROIT, MICHIGAN, A CORPORATION OF MICHIGAN.

RECORDING MECHANISM.

1,265,662.

Specification of Letters Patent. Patented May 7, 1918.

Original application filed July 29, 1901, Serial No. 70,060. Divided and this application filed April 6, 1916. Serial No. 89,349.

To all whom it may concern:

Be it known that I, JOHN T. HOWIESON, a citizen of the United States, residing at New York, in the county of New York and 5 State of New York, have invented certain new and useful Improvements in Recording Mechanism, of which the following is a specification.

This application is a division of my prior 10 application No. 70,060 (series of 1900) filed July 29, 1901, entitled Improvements in calculating machines, upon which Letters Patent No. 1,178,806 have been issued. The present invention relates to control of the 15 inking ribbon through which printing is done. The object is to provide an improved form of means for automatically effecting reversal in the direction of travel of the ribbon. It is carried upon two spools and 20 suitably directed and guided adjacent the platen where it may be shifted into and out of the area through which the type strike. Power for feeding the ribbon lengthwise is supplied by the spring which propels the 25 paper carriage, and I employ power derived from the same source for effecting the shifting of gearing through which the ribbon is wound upon one spool or the other, the ribbon itself timing the shift. Thus in accordance 30 with the present disclosure the ribbon is suitably equipped so that upon being completely unwound from one spool it will unlatch a gear shaft and simultaneously present an abutment for a projection on the shaft 35 to encounter, with the result that the shaft will be shifted and ungeared from the connections for rotating that spool and geared to the connections for rotating the other spool, and the shaft will become latched in 40 the shifted position.

In the drawings which accompany and form part of this specification, Figure 1 is a left side elevation of the machine of my prior application, the casing being partly 45 broken away at the rear to disclose certain parts within; Fig. 2 illustrates the rear portion of said machine in front elevation; Fig. 3 is a horizontal section of the machine taken, substantially on the line 3-3 of Fig. 2; Fig. 50 4 is a horizontal section taken on a higher plane on the line 4-4 of Fig. 1; Fig. 5 is a vertical section taken on the line 5-5 of Fig. 3 looking in the direction of the arrow.

The reference numeral 37 designates the

laterally shiftable paper carriage in which is 55 suitably mounted a roller platen 39; and 96 designates the barrel containing the power spring for propelling the carriage.

At the printing point the ink ribbon A passes through a guide which also serves to 60 center the type, as well as constituting a pointer coöperating with a paper scale. The guide proper consists of a flat plate 504 having a slot 505 which is beveled on opposite sides. This guide is adjustably secured 65 upon a vertical strip 506 pivoted on a vertical frame or bracket 509 which is mounted or secured to a main bracket 57 which extends underneath the carriage mechanism. At its upper end this vertical bracket is open so as 70 to receive the guide proper and prevent any lateral movement thereof. The lower end of the vertical strip which carries the guide piece is connected to the universal bail upon which the keys operate. Normally the guide 75 and its ribbon are removed from immediate proximity to the printing point so that the writing is visible to the operator, but just as soon as any writing key, or in the present instance even a spacing key, is depressed, the guide and ribbon will be thrown forward directly over the printing point and in the path of movement of the type. In case any of the type should be somewhat out of alignment the beveled or inclined sides of 80 the slot in the guide will serve to bring such type in alignment and cause printing at the proper printing point. Consequently this guide also serves the purpose of preserving 85 alignment of the type. 90

The ribbon is carried by two ribbon spools 462 and 463 mounted on brackets 464 supported in any suitable way on the end of the arc 32 or in any other suitable way. The spools are similar in construction and 95 a description of one will apply to both. The spool is mounted upon a shaft 465 bearing in said bracket and adapted to be fastened to such shaft by the knurled nut 466 (Fig. 4). Mounted upon the other end of the shaft is 100 a bevel or miter gear 467 adapted to mesh with a similar but horizontally arranged bevel gear 468 secured to the upper end of a tubular shaft 469 (Fig. 3) which carries at its lower end a bevel gear 470. This tubular shaft bears at its upper end in suitable 105 bearings in the bracket 464, and within such tubular shaft is arranged a vertical rod 471

to whose upper end is secured a lever arm 472 (Figs. 1, 2 and 4) whose rear end is bent or extended into the path of movement of the ribbon and is provided with a slot 473 (Fig. 1) into which the ribbon is received and guided. Any suitable projection or clip, not necessary to be shown, is secured to the ribbon near either end and of such size as to be impossible of passage through said slot or guide 473 which may be termed the reversing guide. The object of the clip or projection is to cause a swinging of this lever 472 and a consequent movement of the rod 471 with the result hereinafter made apparent. The lower end of the rod 471 seats in a suitable bearing in the lower cross rail 321 of the machine.

Now referring to the mechanism associated with the left hand spool the vertical rod 471 is provided near its lower end with an arm 474 to which is pivotally connected a horizontal link 475 which is itself pivoted at its other end to the downwardly extending arm of a bell crank whose horizontal arm 476 consists of a locking lever for the driving pinion as hereinafter explained. The horizontal arm of this bell crank is downwardly sprung pressed by means of a spring 477 (Fig. 5) whereby the tendency is to hold the hook shaped end of such locking lever in engagement with the shaft 478 of the driving bevel pinion 479. The gear 479 on the tubular shaft meshes with a similar gear 480 mounted on the shaft 481 which is provided with bearings 482 arranged upon said cross bar 321. The other end of this shaft 481 has a bevel gear 483 which is adapted to mesh with said driving pinion 479 accordingly as the reversing mechanism shifts such pinion into engagement therewith.

The mechanism associated with the right hand spool is substantially the same in principle as the mechanism just described, but in this case the shaft 484 is longer than the shaft 481, being provided at its right hand end with a gear 485 meshing with its gear 479 and at its other end with a similar gear 486 which is adapted to coöperate with the driving pinion 479. The vertical rod 471 of this right hand spool is adapted to actuate a link or connection 487 which is connected at one end with the upwardly extending arm 488 of a bell crank whose horizontal arm 489 constitutes a locking lever for the driving shaft 478. This particular locking lever is substantially the same as the other locking lever excepting that it is reversed in position being normally upwardly sprung pressed by the spring 490 and with the exception also of the bent or angular construction of the extreme free end, which extends under the other locking lever and at its extremity terminates in a lug or projection 503. The ribbon movement is adapted

to be driven or guided by the tension mechanism belonging to the carriage, and to this end the spring barrel shaft 492 is secured to a pinion 493 and also a ratchet wheel 494. This pinion 493 is one of a train of gears, comprising also an intermediate gear 495 and a lowermost gear 496 secured to one end of the driving shaft 478 hereinbefore referred to. This driving shaft bears in an oscillating bracket 497 which is pivoted upon the stud 498 on the fixed bracket 499, which latter extends forwardly from the rear end frame of the machine, as clearly shown in Figs. 1 and 3.

In the position of the parts shown in Figs. 2 and 3 the mechanism is arranged to cause the winding of the ribbon upon the right hand spool and its unwinding from the other spool inasmuch as the driving pinion 479 is in mesh with the bevel gear 486 and is consequently positively rotating the right hand spool. When, however, the ribbon is almost completely run off from the left hand spool its clip or projection coming into contact with the reversing guide 473 will shift such guide laterally thereby rocking or partially turning the left-hand vertical rod 471 and moving the link 475 to the right. This movement also raises the arm 476 of the bell crank and thereby brings a lug or projection 501 thereon in the path of movement of a pin 502 projecting rearward from the pinion 479, but inasmuch as the projection 501 forms an abutment which is practically immovable with respect to the pin 502 the driving pinion 479 will be shifted just as soon as its pin strikes the projection 501 on said rocking lever or bell crank arm. The spring 490 will now move its locking lever 489 upward thereby allowing a bearing notch therein to straddle shaft and lock it. The driving pinion will now be in mesh with the pinion 483 which is associated with the left hand spool mechanism. Consequently the direction of movement of the ribbon will be reversed and the ribbon will now be wound upon the left hand spool and taken off from the right hand spool. This said movement will continue until the clip or projection near the left hand end of the ribbon has operated its reversing guide and has thereby actuated its bell crank lever, rocking the arm 489 downward and unlocking the shaft and presenting in the path of the pin 502 the projection or abutment 503 formed at the end of said arm 489. Continued rotation of the pinion 479 then results in its being shifted into mesh with pinion 486. Spring 477 pulls down arm 476 and locks the shaft 478, and the parts resume the relative positions shown in the drawings.

I claim:

1. A ribbon movement comprising, in combination with the usual spring barrel as a motor, rotatable spools; separate driven

mechanisms for said spools comprising in connection with gears on the spools, shafts having at one end a gear coöperating with the spool gears and having another gear at 5 the other end; separate shafts adapted to drive the first named shafts; driving mechanism driven by the spring barrel; and means for shifting said driving mechanism into and out of coöperation with said second named shafts.

2. A ribbon movement, comprising rotatable ribbon spools, separate driven mechanisms for said spools, driving mechanism adapted to coöperate with one or the other 15 of the driven mechanisms and comprising a shiftable shaft having a driving pinion, a pair of levers or bell cranks connected with the spool mechanisms and having means of engagement with the shaft, one of said 20 levers coöperating with the driving shaft at any one time, and means controlled by the movement of the ribbon for operating said levers for shifting the driving pinion.

3. A ribbon movement comprising rotatable ribbon spools, separate driven mechanisms for said spools, driving mechanism comprising a shiftable shaft having a driving pinion, a stud on said pinion, levers adapted to coöperate with the driving shaft 30 and having projections adapted to be engaged by said stud, and means controlled by the movements of the ribbon for operating one or the other of said levers whereby the contact of said stud with the projection of 35 the particular operated lever will cause the pinion to shift itself out of engagement with one of said driven mechanisms and into engagement with the other.

4. A ribbon movement comprising rotatable spools, separate driven mechanisms for said spools, driving mechanism comprising a shiftable shaft having a driving pinion, levers controlled by the movements of the ribbon and adapted to coöperate with said shaft, 45 said levers having means for straddling said shaft, one of said levers coöperating with such shaft at any one time, and means whereby said shaft and its pinion is shifted when one or the other of said levers is operated.

5. A ribbon movement comprising rotatable ribbon spools, separate driven mechanisms for said spools, driving mechanism therefor comprising a shiftable shaft having a driving pinion, levers coöperating with 50 said driving shaft and when operated adapted to cause a shifting of the driving pinion, and operating arms adapted to be actuated by said ribbons and to operate said levers.

6. A ribbon movement comprising rotatable ribbon spools, separate driven mechanisms for said spools, a driving mechanism comprising a shiftable shaft having a pinion adapted to coöperate with one or the other 65 of the driven mechanisms, mechanism for

shifting said driving shaft, a pivoted reversing guide or arm through which the ribbon normally passes, and a connection between such guide and said shifting mechanisms.

7. A ribbon movement comprising rotatable ribbon spools, separate driven mechanisms for said spools, a driving mechanism consisting of a shiftable shaft having a pinion adapted to coöperate with one or the other of the driving mechanisms, levers coöperating with the driving shaft and when operated adapted to shift the driving shaft, and reversing guides or arms through which the ribbon normally passes and adapted to be operated by the ribbon and a connection 70 between said guide and levers.

8. A ribbon movement comprising rotatable ribbon spools, separate driven mechanisms for said spools, a driving mechanism comprising a pivoted bearing bracket, a driving shaft bearing in said bracket and having a driving pinion, means for rotating said shaft, mechanism controlled by the ribbon movements for shifting said driving 75 shaft.

9. A ribbon movement comprising, in combination with the usual spring barrel as a motor, rotatable ribbon spools, separate driven mechanisms for said spools, a driving mechanism adapted to coöperate with one or the other of the driven mechanisms and comprising a pivoted bearing bracket, a driving shaft bearing in said bracket and having a driving pinion and also a gear, gearing connections between said spring barrel 85 and said gear, and mechanism controlled by the ribbon movements for shifting said driving shaft.

10. A ribbon movement comprising, in combination with the usual spring barrel 105 as a motor which has a driving gear and a pawl controlled ratchet, a pivoted bracket, a driving shaft in said bracket and having at one end a gear and at the other end a pinion, a gear intermediate said driving gear and the gear on said driving shaft, mechanism for shifting or swinging said driving shaft on the pivot of its bracket, rotatable ribbon spools, separate driven mechanisms for said 110 spools, adapted to coöperate, one at a time, with the pinion on said driving shaft, and means for actuating said shifting mechanism.

11. A ribbon movement comprising rotatable ribbon spools, each having a bevel gear, tubular shafts, one for each spool, each shaft having at one end a bevel gear meshing with the bevel gear on the spools and at the other end another bevel gear, driven shafts having bevel gears at both ends, one of the bevel gears of said last named shafts meshing with one of the bevel gears on the tubular shafts, the two remaining bevel gears on said driven shafts arranged in proximity to each other, a shiftable driving pinion arranged substan- 120 125 130

tially between said adjacent bevel gears, and means for shifting said pinion into engagement with one or the other of said adjacent gears.

- 5 12. A ribbon movement comprising rotatable ribbon spools having bevel gears at their upper ends, meshing with the spool gears, horizontal driven shafts having bevel gears at both ends, two of said bevel gears 10 being brought adjacent to each other, and the other two bevel gears being in mesh with the gears on the lower end of the tubular

shafts, a shiftable driving pinion adapted to coöperate with one or the other of said adjacent gears, shifting mechanism coöperating 15 with said driving pinion, a rod passing through each of said tubular shafts, a connection between the lower end of said rod and said shifting mechanism, and a reversing guide coöperating with the ribbon and 20 connected to the upper end of said rods.

JOHN T. HOWIESON.

In presence of—

WALTER CREETHAM.
